UNITED STATES PATENT OFFICE.

HENRI ARNOLD JOHANNES DE BIJLL NACHENIUS, OF HAARLEM, NETHERLANDS.

VESSEL PROPELLED BY GAS DISCHARGED BELOW THE WATER LEVEL.

Application filed July 3, 1922. Serial No. 572,583.

To all whom it may concern:

Be it known that I, HENRI ARNOLD JOHANNES DE BIJLL NACHENIUS, a subject of the Queen of the Netherlands, residing at Haarlem, Netherlands, have invented certain new and useful Improvements in Vessels Propelled by Gas Discharged Below the Water Level, of which the following is a specification.

10 This invention relates to an improvement in or modification of vessels adapted to be propelled by gas (usually air) discharged below the water level with a pressure which does not appreciably exceed the water pressure at the outlet, and having a substantially plane, upwardly inclined stern face for guiding the rising gas bubbles.

In the drawings,

Figure 1 is a side view of the stern without the horizontal extension.

Figure 2 is a side view of the device in operation.

Figure 3 is a side view of a slight modification.

25 Figure 4 is a side view of the vessel showing the position of the gas outlet.

The gas bubbles rising to the water level along the inclined plane forming the stern face 1 (see Figure 1) which extends through the entire or the greater part of the width of the vessel produce a water current in substantially parallel relation with the stern face. Said current has, of course, a tendency to continue its movement in the same direction above the water level but this is prevented by the action of gravity, that is to say, a wave is formed at the stern of the vessel as indicated by *a* (Figure 1). This wave formation means a loss of energy as 40 the energy required for lifting the water above the water level cannot be used for propelling the vessel.

45 The gas outlet is positioned along the bottom of the vessel, as shown at 3, of Figure 4. Of course several outlets might be used if desired, one only being shown in the drawing.

50 The object of the present invention is to reduce this loss of energy. In accordance with the invention the wave formation at the stern of the vessel may be avoided or reduced by securing to the vessel, approximately flush with the water level, a horizontal plate 2 (Fig. 2) which extends 55 through substantially the full width of the

vessel so as to constitute the end portion or the extension of the inclined face 1. This plate has for its duty to impart just at the water level a horizontal movement to the water current rising along the face 1 in a 60 direction opposite to that of the vessel, whereby the full reaction of the water current is available for propelling the vessel. Practical tests have already shown that by these means it is indeed possible to increase 65 the speed of the vessel.

Assuming the velocity of the water current along the inclined stern face to be *v* and the angle between said face and a horizontal plane to be *α*, the component producing the wave formation is $v \sin \alpha$. This component is almost entirely transformed by the horizontal plate 2 into an increase of pressure of the uppermost water strata. Said increase of pressure, corresponding 75 with a head of water of

$$\frac{v^2 \sin^2 \alpha}{2g}$$

increases the speed of the vessel and also the 80 velocity of the water current in the opposite direction.

It is obvious that the effect of the horizontal plate 2 is maximum when said plate is arranged exactly at the water level. With 85 a view to the varying draught of the vessel said plate should, therefore, be vertically adjustable, that is to say, it should be secured at the required level to the vessel every time the latter begins a voyage. This, however, meets in many cases with serious difficulties. With a view to this fact the stern face of the vessel may be made concave (viewed from the side), either broken or curved, in such a manner that the tangent to this surface forms with the horizontal plane an angle which at the maximum draught is 90° at the water level and which gradually increases downwardly (see Figure 3 of the drawing). If, now, the draught of the vessel is maximum, the wave formation is completely prevented by the horizontal portion 95 of the stern face, whereas at a decreased draught, within a certain limit, still a useful effect is obtained over the construction 100 shown in Figure 2.

What I claim is:

1. In a vessel adapted to be propelled by gas discharged below the boat bottom with no appreciable over-pressure, an upwardly 110

sloping stern face for guiding rising gas bubbles from the boat bottom to the surface of the water, said stern face extending substantially the entire width of the vessel, and having an approximately horizontal extension surface substantially flush with the water level.

2. In a vessel according to claim 1, said

upwardly sloping stern face being concave. ¹⁰
3. In a vessel according to claim 1, the said approximately horizontal surface being vertically adjustable with respect to the vessel.

In testimony whereof I affix my signature.
HENRI ARNOLD JOHANNES
de BIJLL NACHENIUS.
